ABSTRACT

An improved stationary cutter element for use with the rotating cutter ring of a circular hosiery knitting machine having contiguous peripheral teeth extending into close proximity to the rotating circle of needles. The cutting edge of the stationary cutter element is properly shaped to be cammed upwardly as it engages the radially extending leading edges of successive teeth to provide a scissors action therewith and effectively cut any yarn engaged thereby.

YARN CUTTER FOR HOSIERY KNITTING MACHINES

This invention relates to improved yarn severing or cutting means for circular hosiery knitting machines of the type which include a rotating cutter ring provided with peripheral teeth extending into close proximity to the circle of needles and adapted to engage yarns introduced and withdrawn from the needles.

In order to eliminate the long yarn ends which are produced by cutting devices supported on the inner portion of the dial of a circular hosiery knitting machine, most circular hosiery knitting machines are currently provided with a rotating cutter ring having teeth extending into close proximity with the circle of needles and with some type of stationary cutter blade or element which is maintained in engagement with the teeth. The stationary cutter blade operates to cut any yarns engaged by the teeth and brought into engagement with the cutter blade so that the yarn ends are cut closely adjacent the hosiery fabric. Many different types of stationary cutting blade elements have been proposed for use in cooperation with the rotating cutter ring.

These prior types of stationary cutter blades do not produce satisfactory yarn cutting results over a long period of time and the stationary cutter blade must be frequently resharpened so that a clean and reliable cut is assured. Also, the known types of stationary cutter blade elements are not provided with means to accurately position the same so that they operate satisfactorily with the rotating cutter ring. The known types of stationary cutter blades also fail to cut on occasion, because of foreign substances being carried under the cutter blade by the rotating cutter ring so that the cutter blade is raised from the surface of the ring.

With the foregoing in mind, it is an object of the present invention to provide an improved stationary cutter blade for cooperation with the rotating cutter ring which operates to effectively cut the yarn ends over a long period of time and while requiring very little attention on the part of the operator.

It is another object of the present invention to provide an improved stationary cutter blade which may be easily adjusted into proper setting relationship with the teeth of the rotating cutter ring and wherein the action between the cutting edge of the successive teeth and the cutting edge of the stationary cutter blade provides a scissors action which insures the effective cutting of the yarn.

In accordance with the present invention, the improved cutter includes a substantially rectangular lower end having a leading cutting edge extending at an acute angle and an outside edge extending at a right angle from the leading cutting edge to provide an outer cutter point at their juncture. The leading cutting edge extends upwardly and inwardly from the outer cutter point and the outside edge extends upwardly and rearwardly from the outer cutter point to provide what may be termed a "compound angle" on the lower end of the cutter element. Resilient means is provided for urging the cutter element downwardly into engagement with the upper surface of the cutter ring so that the leading cutting edge is cammed upwardly as it engages the radially extending leading edges of successive teeth of the rotating cutter ring to provide a scissors action therewith and effectively cut any yarn engaged thereby. Air under pressure is directed downwardly against the upper surface of the rotating cutter ring and immediately in advance of the cutter blade to remove any foreign substance being carried toward the stationary cutter blade by the cutter ring.

Other objects and advantages of the present invention will become apparent in connection with the following detailed description of the drawings, in which—

FIG. 1 is a fragmentary isometric view of a portion of the dial of a circular hosiery knitting machine and illustrating the stationary cutter blade of the present invention associated with the rotating cutter ring;

FIG. 2 is a vertical sectional view at an enlarged scale and being taken substantially along the line 2—2 in FIG. 1;

FIG. 3 is a vertical sectional view taken substantially along the line 3—3 in FIG. 2;

FIG. 4 is an enlarged horizontal sectional view taken substantially along the line 4—4 in FIG. 1; and

FIG. 5 is a greatly enlarged fragmentary front elevational view of the lower portion of the stationary cutter blade and a small portion of the rotating cutter blade to illustrate the manner in which the compound angle on the lower end of the cutter blade cooperates with the teeth of the cutter ring.

Only those portions of a circular hosiery knitting machine are illustrated which are necessary to an understanding of the present invention. As is well known, most circular hosiery knitting machines currently in use are of the multiple feed type and are provided with a plurality of yarn feeding and knitting stations spaced around the needle cylinder so that a plurality of courses are knit with each rotation of the needle cylinder. A stationary dial is supported inside of the rotating circle of needles, as indicated at N in FIG. 4, and usually includes a dial plate 10. The dial plate supports the usual cams, not shown, for controlling the radial position of transfer bits 11 (FIG. 3) which are supported in the radial grooves of a rotating dial bed 12, rotating in timed relationship with rotation of the circle of needles N. A rotating cutter ring 13 is supported for rotation on the dial plate 10 and is rotated in time relationship to rotation of the circle of needles N by a driving connection with the dial bed 12.

Contiguous teeth are provided on the rotating cutter blade 13 and each of the teeth includes a radially extending leading edge 14 and a trailing edge 15 which extends at an acute angle from the radially extending leading edge 14. The peripheral teeth extend into close proximity with the circle of needles N and are adapted to engage yarns introduced and withdrawn from the needles during the knitting of ladies' seamless hosiery and the like.

As is well known, yarn feed fingers, not shown, are provided for introducing and withdrawing yarn to the needles at each knitting station. When a yarn is introduced, the first needle to knit pulls the yarn downwardly from where its terminal end is held by suitable means, such as a suction nozzle 20. The suction nozzle 20 is supported in a suitable dial cap 21 so that the yarn is drawn downwardly and over the rotating cutter ring 13. As the cutter ring 13 rotates with the circle of needles N, the corresponding leading edge 14 of a tooth carries the yarn around with the needles until it engages and is cut by the stationary cutter blade, to be presently described.

When a yarn is withdrawn from active position, the corresponding yarn feed finger is raised so that the yarn extending from the last needle to knit is engaged by the leading edge 14 of a tooth on the rotating cutter ring 13 and is carried around the needle cylinder until it engages the fixed cutter blade. Upon severing of this withdrawn yarn, the cut free end is drawn up into the suction nozzle 20 and held until the yarn is again introduced. Suction is provided beneath the dial cap to attract the yarn ends up into the suction nozzle 20 by means of an air pressure line 22 which directs air upwardly in the suction nozzle 20.

In accordance with the present invention, an outwardly extending flange or skirt-like extension is provided on the dial cap 21 and ahead of the stationary cutter element. This skirt-like extension 25 extends downwardly and overlies the outer edge of the teeth of the rotating cutter blade 13 and provides a tunnel like entranceway above the upper surface of the rotating cutter blade 13 and in advance of the stationary cutter blade. A vertically extending opening 26 is provided in the extension 25 to provide an opening for operation of the stationary cutter of the present invention, broadly referred to at C.

The stationary cutter C includes an elongate cutter element 65 which is substantially rectangular in cross-section and has a vertically disposed upper stem portion 30. The upper stem portion 30 is supported for vertical movement in a guide slot or groove 31 cut in a vertical portion 32 of a support bracket having a horizontal leg 33. The horizontal leg 33 is fixedly secured to the dial cap 21 by screws 34. Suitable adjustment screws 35, 36 (FIG. 3) are threadably supported in one side of the vertical housing portion 32 and a single adjustment screw 37 is threadably supported in the opposite side of the housing 32 and substantially half way between the screws 35, 36. The slot 31 is considerably wider than the width of the stem por-

tion of the fixed cutter C and the inner ends of the adjustment screws 35, 36 and 37 may be adjusted to vary the vertical position of the stem portion 30, for purposes to be presently described.

A spring perch, in the form of a screw 40, is threaded through the upper end of the stem portion 30 and supports the upper end of a tension spring 41. The lower end of the tension spring 41 is fixed in a bore 42 extending vertically in the vertical housing portion 32 (FIG. 2). The tension spring 41 thus resiliently urges the cutter element C downwardly so that its lower end is resiliently maintained in engagement with the upper surface of the rotating cutter ring 13.

The lower end portion of the fixed cutter C is substantially rectangular and includes a hardened steel blade element which is suitably brazed to the leading surface thereof. The lower end of the cutter C includes a leading cutting edge 44 (FIG. 4) extending at an acute angle which substantially corresponds to the angular disposition of the trailing edges 15 of each of the teeth on the rotating cutter blade 13. An outside edge 45 is also provided at the lower end of the cutter blade C and extends at a right angle from the leading edge 44. The juncture of the leading cutting edge 44 and the outside edge 45 defines an outer cutter point 46 which constitutes the lowermost point of the lower end of the cutter C (FIG. 5). As shown in FIG. 5, the lower end of the cutter blade is cut at a compound angle with the leading cutting edge 44 extending upwardly and inwardly from the outer cutter point 46 at a slight angle of approximately one-half degree as indicated at A. The outside edge 45 extends upwardly and rearwardly from the outer cutter point 46 at a slight angle of approximately 3°, as indicated at B.

The adjustment screws 35, 36, and 37 are regulated so that the outer cutting point 46 is positioned to correspond with the outer extremities of the teeth on the cutter ring 13, substantially as shown in FIG. 4. As the teeth of the cutter ring 13 move beneath the cutter blade C, the leading edge 14 of each tooth engages the inclined leading edge 44 of the cutter and a camming action takes place so that the leading cutting edge is cammed upwardly as the radially extending leading edge 14 of the tooth moves to the outer cutter point 46. This camming action provides a scissors action therewith to effectively cut any yarn brought therebeneath by the teeth.

As the outer end of a tooth moves into alignment with the lower cutter point 46, the cutter blade C is raised slightly. With further movement of the ring 13, the cutter blade C is lowered slightly as the trailing edge 15 of the tooth engages the inclined outside edge 45 so that the outer cutter point 46 is actually positioned below the upper level of the rotating cutter blade 13, as shown in FIG. 5. With further rotation of the cutter 13, the cutter blade C is again raised slightly as the leading edge 14 of the next tooth engages the leading cutting edge 46 and cams the same upwardly.

Thus, a scissors action takes place between the leading edge 14 of each tooth and the leading edge 44 of the fixed cutter C as each tooth of the rotating ring 13 passes therebeneath. This scissors action insures that any yarn carried therebeneath by the teeth will be accurately and effectively cut.

In order to prevent foreign matter from being brought beneath the fixed cutter C by the rotating blade 13, the lower end of an air pressure tube 50 is positioned in the opening 26 and is positioned closely adjacent the leading cutting edge 44. The air pressure tube 50 extends upwardly (FIG. 1) and its upper end is supported in a support bracket 51 which is suitably secured to the vertical housing portion 32. An air pressure branch line 52 is connected at one end to the upper end of the tube 50 and its other end is suitably connected to the air pressure line 22. Thus, air under pressure is continuously directed downwardly against the upper surface of the blade 13 (FIG. 4) and moves outwardly along the blade to remove any lint, yarn ends, and the like which would become trapped under the cutter C.

Although the cutter C is illustrated as being resiliently urged into the engagement with the upper surface of the rotating

cutter blade 13 in a continuous manner, it is to be understood that this cutter blade may be adapted to be raised to an inoperative position when no yarn ends are to be cut.

In the drawings and specification, there has been set forth a preferred embodiment of the invention, and although specific terms are employed, they are used in a generic and descriptive sense only and not for purposes of limitation.

What is claimed is:

1. In a circular hosiery knitting machine including a circle of needles supported for rotation, a stationary dial supported inside of said circle of needles, a cutter ring mounted for rotation on said stationary dial and having contiguous peripheral teeth extending into close proximity to said circle of needles, each of said teeth including a radially extending leading edge and a trailing edge extending at an acute angle therefrom, said leading edges being adapted to engage yarns introduced and withdrawn from the needles, the combination therewith of an improved cutter supported on said dial and comprising
  - a. an elongate cutter element including a substantially rectangular lower end defining a leading cutter edge extending at an acute angle substantially corresponding to the acute angular relationship of said trailing edges of said teeth, and an outside edge extending at a right angle from said leading cutting edge,
  - b. the juncture of said leading cutting edge and said outside edge defining an outer cutter point corresponding with the outer extremities of said teeth,
  - c. said leading cutting edge extending upwardly and inwardly from said outer cutter point at a slight angle, and said outside edge extending upwardly and rearwardly from said outer cutter point at a slight angle so that said outer cutter point is the lowermost point of the lower end of said cutter element, and
  - d. means resiliently urging said cutter element downwardly into engagement with the upper surface of said cutter ring so that said leading cutting edge is cammed upwardly as it engages said radially extending leading edges of successive teeth of said rotating cutter ring to provide a scissors action therewith and effectively cut any yarn engaged thereby.

2. A cutter according to claim 1 wherein said elongate cutter element includes a vertically disposed upper stem portion, and means for adjusting the vertical position of said upper stem portion to thereby vary the position of said outer cutter point relative to the outer extremities of said teeth.

3. A cutter according to claim 2 including a support bracket carried by said stationary dial and comprising a vertical housing portion with a vertical groove therein for slideably supporting said stem portion, and wherein said adjusting means comprises a pair of spaced apart screws extending through said vertical housing portion with their inner ends in engagement with one side of said stem portion, a single screw extending through said vertical housing portion with its inner end in engagement with the other side of said stem portion, and said single screw being spaced substantially half the distance between said pair of screws.

4. A cutter according to claim 3 wherein said housing portion includes a vertically disposed bore extending parallel to said vertical groove, and wherein said resilient means (d) comprises a tension spring having an upper end connected to the upper end of said stem portion and having a lower end connected adjacent the lower end of said bore.

5. A cutter according to claim 1 including a hardened steel plate fixed on the lower leading edge of said cutter element.

6. A cutter according to claim 1 including means for directing air under pressure onto the upper surface of said cutter ring and in front of said cutter element to remove foreign substances carried toward said cutter element by said cutter ring.

7. A cutter according to claim 6 wherein said stationary dial includes a dial plate and a dial cap overlying said dial plate, a skirt-like extension extending outwardly from said dial cap and over said cutter ring and having an opening therein to receive said cutter element, and wherein said air pressure

directing means comprises an air pressure tube extending through the opening in said skirt-like extension and having a free end terminating above said cutter ring.

8. A cutter according to claim 1 wherein said leading cutting edge extends upwardly and inwardly at an angle of ap-

proximately one-half of a degree.

9. A cutter according to claim 1 wherein said outside edge extends upwardly and rearwardly at an angle of approximately 3°.
